RIDER PROPELLED AQUATIC DEVICE
FOR BATHERS

Roy E. Jones, Batesville, Miss.

Application November 14, 1947, Serial No. 786,112

3 Claims. (Cl. 9—18)

1

This invention relates to an aquatic device adapted to be ridden and propelled by a bather and more particularly pertains to a relatively light vessel including a buoyant body on which a bather is adapted to ride and having means for propelling the device by operation of the feet and means for steering the device with the hands.

Another object of the invention is to provide a rider propelled vessel having a rudder and propeller swingable with respect to the hull to enable the device to be readily steered even at very slow speed and which parts are located remote to the manually actuated means for accomplishing the steering.

Another object of the invention is to provide a vessel having a water tight hull defining an air chamber and supported on a tubular frame forming a housing for the power transmitting and steering connections of the device.

Still another object of the invention is to provide a device or vessel of the aforescribed character which will be extremely safe in use, which is durable yet light in weight and by means of which a bather riding thereon may readily propel the vessel at considerable speed through the water.

Still a further object of the invention is to provide a device which will afford considerable amusement and exercise in the water and which could otherwise not be accomplished by non-swimmers.

Various other objects and advantages of the invention will hereinafter become more fully apparent from the following description of the drawings, illustrating a presently preferred embodiment thereof, and wherein:

Figure 1 is a perspective view of the rider propelled aquatic device shown in operative position;

Figure 2 is a perspective view of the frame thereof;

Figure 3 is an enlarged longitudinal sectional view, partly in side elevation and on a vertical plane taken through the forward portion of the frame;

Figure 4 is a similar view taken through the rear portion of the frame;

Figure 5 is a horizontal sectional view taken substantially along a plane as indicated by the line 5—5 of Figure 4;

Figure 6 is a transverse vertical sectional view taken substantially along a plane as indicated by the line 6—6 of Figure 4;

Figure 7 is a horizontal sectional view taken 55

2

substantially along a plane as indicated by the line 7—7 of Figure 4, and

Figure 8 is a fragmentary cross sectional view through a portion of the hull of the device.

Referring more specifically to the drawings, the novel rider propelled aquatic device comprising the invention is designated generally 10 and includes a water tight hull 11 which is preferably formed of aluminum but which may be formed of other light weight, water proof material. The hull 11 is secured around a frame designated generally 12 of tubular construction and which includes an upper longitudinal tube 13, a lower tube 14 which converges upwardly and forwardly with respect to the tube 13 and which is joined thereto or formed integral therewith at the forward ends thereof by an enlarged socket portion 15. The rear, vertically spaced ends of the tubes 13 and 14 merge with and open into a perpendicular housing portion 16. The frame 12 is provided with a plurality of longitudinally spaced ribs 17 which are secured to the tubular frame portions 13 and 14 and by means of which the hull 11 is held in an extended position and provided with a substantially flat relatively wide intermediate top portion which tapers toward both ends of said hull and over which is secured a pad of a suitable cushioning material such as sponge rubber, as indicated at 18 and best seen in Figure 8. As best illustrated in Figure 4, the perpendicular housing 16 is provided with a closed bottom and is in communication with the frame portion 14 adjacent thereto. The housing 16 is open at its top and contains an inner tubular member 19, the lower end of which terminates adjacent said open top and which is provided with a flanged open upper end 20 which extends to substantially above the top of the housing 16. The tubular member 19 is secured to the upper end of the housing 16 by soldering or welding, as indicated at 21 and the rear ends of the tubular frame portions 13 and 14 may likewise be secured to the housing 16 by soldering or welding, also as indicated at 21. The housing 16 adjacent its bottom is provided with a rearwardly extending flanged opening 22 which is elongated in a direction circumferentially thereof and the ends of which diverge outwardly with respect to one another, as best illustrated in Figure 6. The bottom portion of the housing 16 contains a tubular liner or sleeve 23 which is closed at its bottom and the bottom portion of which rests on the bottom of said housing 16. The liner 23 is open at its top and terminates below the level of the tubular member 19. The liner 23 is pro-

vided adjacent its bottom with a radially projecting bearing 24 which extends rearwardly and outwardly through the flanged opening 22 and which is swingably disposed therein. The liner 23 makes a sufficiently close engagement with the bottom portion of the housing 16 to combine therewith to seal the opening 22 against entrance of water into said housing. A propeller shaft 25 extends through and is journalled in the bearing 24 and said bearing is provided with inwardly opening grooves containing packing 26 to provide a water tight seal between the bearing 24 and shaft 25. A propeller 27 is secured to the rear end of the shaft 25 and rearwardly of the bearing 24 by a shear pin 28 and a rudder 29 which is fixedly secured to the rear end of the bearing 24, outwardly of the flanged opening 22, is provided with an opening 30 in which the propeller 27 is disposed for rotation and which forms a protecting frame therearound to protect the propeller from obstructions.

A beveled gear 31 is keyed to the inner end of the propeller shaft 25 and is disposed within the liner 23 and meshes with a beveled gear 32 which is keyed to the lower end of a drive shaft 33 which extends longitudinally through the housing 16 and is journalled in spaced antifriction bearings 34, one of which is secured in the liner 23 and the other of which is secured in said tubular member 19. A beveled gear 35 is keyed to the upper end of the shaft 33 and is disposed adjacent the open upper end of said tubular member 19 for meshing engagement with a beveled gear 36 which is keyed to a shaft 37. The shaft 37 extends diametrically through a cover member 38 having an open, externally flanged bottom 39 which seats on and is detachably secured to the flange top 20 of the tubular member 19 by fastenings 40. A gasket or other water tight seal 41 is disposed between the flanged portions 20 and 39 and it will be readily apparent that the cover 38 functions to completely close the housing 16, when in an applied position. As best seen in Figure 2, the shaft 37 is provided with cranks 42 at the ends thereof on each of which is journalled a pedal 43 equipped with a foot retaining strap or stirrup 44 and it will be readily obvious that when the shaft 37 is revolved the shafts 33 and 25 will be driven thereby through the beveled gears, previously described, for revolving the propeller 27 the blades of which are pitched so that when the shaft 37 is revolved counterclockwise, as seen in Figures 1 and 2, said propeller 27 will be revolved in a direction for propelling the vessel 10 forwardly or from right to left of Figure 1.

Referring particularly to Figure 3, socket 15 is provided with an externally threaded open top normally closed by a threaded cap 45 having a centrally disposed boss 46, equipped with a water seal and through which a steering post 47 extends. The steering post 47 is rotatably disposed in the boss 46 and is journalled in an antifriction bearing 48 contained in said socket 15. The post 47 is provided at its upper end and above the cap 45 with a sleeve portion 49 which is disposed transversely thereof and in which the intermediate portion of a handle bar 50 is suitably secured. A beveled gear 51 is keyed to the lower end of the post 47 and meshes with a beveled gear 52 which is keyed to the forward end of a shaft 53 which extends longitudinally through tubular frame portion 14 and is journalled in bearings 54, contained therein. The opposite, rear end of the shaft 53, as seen in Figure 4, has a crown gear 55 keyed thereto and

which is disposed at an angle to the housing 16 and has its upper portion extending into said housing so that the teeth thereof mesh with a ring of externally disposed, circumferentially spaced notches 56 formed in the liner 23 whereby when the handle bar 50 is swung to operate the steering post 47 the shaft 53 will be turned thereby causing the crown gear 55 to be turned in one direction or the other for oscillating the liner 23 within the housing 16 to cause the bearing 24, propeller 27 and rudder 29 to be swung relatively to said housing 16 for steering the vessel 10.

The frame 12 is preferably provided with shoulder engaging members 57 which are preferably secured to certain of the ribs 17 and extend upwardly therefrom through the top portion of the hull 11 and through the pad 18 to be engaged by the shoulders of the rider of the vessel 10, as illustrated in Figure 1.

From the foregoing it will be readily apparent that a bather, as indicated in Figure 1, may lie prone on the stomach on the pad 18 with the shoulders engaging against the shoulder rests 57 and with the hands grasping the ends of the handle bar 50. The legs straddle the rear end of the hull 11 when the feet engage the pedals 43 and are held thereon by the stirrups 44. The hull 11 will float buoyantly on the water but with the rear lower portion thereof submerged so that the propeller 27 and rudder 29 will be under water. By rotating the crank shaft 37 counterclockwise, as previously described, the propeller 27 will be revolved for propelling the vessel 10 forwardly or from right to left and said vessel can be readily steered by turning the handle bar 50 toward the direction that it is desired to turn the vessel and so that the liner 23 and the propeller 27 and rudder 29, carried thereby will be swung relatively to the housing 16 for readily causing the vessel 10 to execute turning movements even at very slow speed.

Obviously, the aquatic device 10 may be made in various sizes for accommodating adults and children and the shoulder rests 7 may be spaced at various distances from the crank shaft 37, and, if desired, said shoulder rests could be adjustably secured for longitudinal displacement relatively to the hull 11.

Various other modifications and changes are likewise contemplated which may obviously be resorted to, without departing from the spirit or scope of the invention as hereinafter defined by the appended claims.

I claim as my invention:

1. A rider propelled aquatic device comprising a buoyant hollow hull having a top, occupant supporting surface, a tubular frame substantially enclosed by said hull, a propeller journalled in a portion of the frame and disposed rearwardly of the hull, pedal and crank means journalled transversely of the frame and above the rear end of the hull and adapted to be engaged and actuated by the feet of the occupant, driving means journalled in said frame and forming a driving connection between the propeller and pedal and crank means, means for swingably mounting the propeller relatively to the rear end of said hull and to the pedal and crank means, and manually actuated steering means disposed adjacent and above the forward end of the hull and connected to said last mentioned means and adapted to be actuated by the occupant for steering the device.

2. An aquatic device as in claim 1, said steering means comprising a handle bar disposed above

the forward end of the hull, a steering post secured thereto and journaled in said frame, a steering shaft journaled in the frame and connected to the steering post for rotation thereby, said means for swingably mounting the propeller comprising a vertically journaled swivelly mounted upright liner member disposed in the rear hull portion and by which said propeller is rotatably supported, and means connecting said steering shaft to said liner for oscillating the liner in the frame when the handle bar is swung relatively to the hull. 10

3. An aquatic device as in claim 1, said steering means comprising a handle bar disposed above the forward end of the hull, a steering post secured thereto and journaled in said frame, a steering shaft journaled in the frame and connected to the steering post for rotation thereby, said means for swingably mounting the propeller comprising a vertically journaled swivelly mounted upright liner member disposed in the rear hull portion and by which said propeller is rotatably supported, and means connecting said steering shaft to said liner for oscillating the liner in the frame when the handle bar is swung 25

relatively to the hull, said liner including a propeller shaft bearing projecting rearwardly from the frame and swingably disposed with respect to the frame, and a rudder secured to said bearing and disposed in substantially a vertical plane for swinging movement relatively to the hull in response to the swinging movement of the handle bar and in unison with the propeller.
